UNITED STATES PATENT OFFICE

FRANK FREDERICK POLAND, OF BALTIMORE, MARYLAND, ASSIGNOR TO AMERICAN SMELTING AND REFINING COMPANY, OF NEW YORK, N. Y., A CORPORATION OF NEW JERSEY

ELECTROLYTIC CELL

Application filed February 11, 1928. Serial No. 253,556.

This invention relates to electrodes for electrolytic cells and more particularly to an electrode capable of carrying a heavy current without excessive losses.

The invention may be applied specifically to a means for supporting a heavy electrode and for carrying current thereto. In a type of electrolytic cell used in processes in which an extremely heavy current strength is required, such as for example metal refineries where a current strength of 12,000 amperes may be employed, means is provided for suspending the heavy electrode from a supporting bar and for making an electrical contact 10 between the electrode and the bar which has an extremely low resistance whereby the resistance losses are reduced to a minimum.

In accordance with the present invention, the electrode is supported from the electrode bar by means of a shroud having a substantial width and so formed on its inner surface that a full surface contact may be obtained with the bar. The particular form of shroud depends largely upon the contour of the supporting bar and should be such that a maximum area of contact is obtained between the two elements.

The invention also consists in certain new and original features of construction and 30 combinations of parts hereinafter set forth and claimed.

Although the novel features which are believed to be characteristic of this invention will be particularly pointed out in the claims 35 appended hereto, the invention itself, as to its objects and advantages, the mode of its operation and the manner of its organization may be better understood by referring to the following description taken in connection with the accompanying drawings 40 forming a part thereof, in which

Fig. 1 is an elevation partly in section of an electrolytic cell having an electrode constructed in accordance with this invention; 45 and

Fig. 2 is a section taken on line 2-2 of Fig. 1 showing the electrode supporting shroud.

Like reference characters denote like parts 50 in the several figures of the drawings.

In the following description and in the claims parts will be identified by specific names for convenience, but they are intended to be as generic in their application to similar parts as the art will permit.

The particular embodiment of the invention which has been shown in the drawings for purposes of illustration, comprises an electrolytic cell having side walls 10 and an interior wall 11 by means of which the cell is divided into two parts. An electrode 12, as for example the anode, is provided with a pair of ears 13 which rest upon supporting members 14 upon walls 10 and 11 respectively. The other electrode 15, as for example the cathode, is supported from a cathode bar 16 which rests at one end upon supporting member 17 in contact with wall 10. At the other end, bar 16 makes contact with and is supported by ear 13 of anode 12. A suitable groove may be provided in ear 13 to receive the end of bar 16 as indicated in Fig. 1. The upper portion of bar 16 may be provided with a plurality of surfaces 20, 60 21 and 22 (Fig. 2) in order to increase the area of contact between said bar and shroud 23 as will be described.

Cathode 15 is hung from cathode bar 16 as by shroud 23 which is passed over said bar and secured at its two ends to opposite sides of said cathode as by bolts or rivets 80 25. A sufficient number of bolts should be employed to cause the shroud to firmly engage the sides of cathode 15 and to make a low resistance electrical connection therewith. The upper portion of shroud 23 is preferably formed with a contour corresponding to that of top surface of bar 16 whereby engagement may be made with each of the surfaces 20, 21 and 22 of said bar. 85 The sides of shroud 23 are preferably formed to contact with the sides of bar 16 although it is obvious that the top surfaces will be under greater pressure due to the weight of cathode 15 and will be more important in determining the total resistance of the connection.

The internal surface of shroud 23 in addition to being formed in section corresponding to rod 16 is preferably formed sufficiently 95 100

flat in a longitudinal direction to enable a contact to be made with bar 16 through the entire length of said shroud. This condition has heretofore been particularly difficult to obtain in cases where more than one shroud is employed for supporting the cathode, since the interior surface of each shroud must be formed straight in a longitudinal direction and they must be properly aligned to enable 10 a surface contact to be obtained rather than a line contact.

A particular source of loss of power through the contacts of the supporting members for the electrodes is the corrosion of the material, which begins at the edges of the shroud and penetrates inwardly toward the center thereof for a limited distance. By providing a single wide shroud only, two points are provided at which the corrosion 20 may be initiated and the total penetration thereof, being substantially constant irrespective of the shroud width, is reduced to a smaller percentage of the total area involved. The use of a single wide shroud, therefore, 25 in place of a narrow shroud, or a plurality of narrow shrouds, not only gives a positive line contact between the shroud and the cathode bar, but limits the amount of corrosion in proportion to the shroud width.

30 It has been found in practice that the electrical properties of a shroud constructed in accordance with this invention are considerably in excess of those heretofore obtained, principally due to the increased surface of 35 contact and to the limited proportion of corrosion and also to the fact that it is practically impossible for workmen to assemble the apparatus with the parts out of alignment. The increased weight in metal involved in the wide shroud is more than offset 40 by the reduced labor cost due to the elimination of a plurality of surfaces which had been heretofore employed, requiring accurate alignment to obtain the necessary surface 45 contact. It has been found in practice that the above type of shroud materially reduced the voltage drop of the electrode connection and served to increase the life of the various parts. The saving in labor and in current 50 losses were considerable in the case of a large commercial installation.

55 While certain novel features of the invention have been shown and described and are pointed out in the annexed claim, it will be understood that various omissions, substitutions and changes in the forms and details of the device illustrated and in its operation may be made by those skilled in the art without departing from the spirit of the invention.

60 What is claimed is:

65 A combination of an electrolytic cell, an electrode support therefor comprising a single U-shaped shroud, means for securing said shroud to said electrode, means for supporting said shroud from a supporting rod,

the cross section of said rod and of said shroud being substantially identical and said members being formed with horizontal and inclined supporting surfaces and substantially straight longitudinal surfaces whereby a large effective area of contact is obtained therebetween.

70 In testimony whereof I have hereunto set my hand.

FRANK FREDERICK POLAND.
